DOOR CHECK

Frederick J. Westrope, Pleasant Ridge, Mich., assignor, by mesne assignments, to Reconstruction Finance Corporation, Detroit, Mich., a corporation of the United States

Application January 22, 1940, Serial No. 314,920

5 Claims. (Cl. 16—86)

This invention relates generally to devices for checking opening movement of a hinged door, and more particularly to a device for checking the opening movement of a motor vehicle door 5 and for releasably holding the door in an open position.

It is an object of the present invention to provide a new and improved device for checking opening movement of a motor vehicle door and 10 for also releasably holding the door in an open position.

Another object of the invention is to provide new and improved buffer means for retarding opening swinging movement of a motor vehicle 15 door and for yieldingly holding the door in an open position.

A further object of the invention is to provide a device of the above mentioned character which is inexpensive to manufacture but which 20 is efficient in operation.

Other objects of the invention will become apparent from the following detailed description taken in connection with the accompanying drawings, in which—

25 Fig. 1 is a fragmentary view in horizontal section of a vehicle body door frame and door and my improved door check and releasable holder associated therewith;

Fig. 2 is a vertical sectional view partly in elevation of the structure shown in Fig. 1;

Fig. 3 is a view similar to Fig. 1 but with the door shown in an open position;

Fig. 4 is a view similar to Fig. 3 showing the door in its extreme open position in which position the door is releasably held against swinging closed;

Fig. 5 is a fragmentary view taken along the line and in the direction of the arms 5—5 of Fig. 2, having parts broken away and in section 40 to show certain details of construction;

Fig. 6 is a perspective view of a part of the device shown removed therefrom;

Fig. 7 is a view partly in elevation and partly in section of the cooperating door check parts, 45 taken along the line and in the direction of the arrows 7—7 of Fig. 3, and

Fig. 8 is a view similar to Fig. 7 taken along the line 8—8 of Fig. 4.

Referring to the drawings by characters of 50 reference, the numeral 10 designates in general, a vehicle body, vertical door frame member or hinge pillar on which a door 11 is mounted by suitable vertically spaced hinges 12, the pillar 10 and the door 11 having opposed end walls 13 and 14 respectively which are recessed to

receive respective leaves of the hinges. Within the pillar 10, a reenforcing or backing plate 15 is secured to the pillar wall 13, the plate 15 and wall 13 having aligning apertures to receive a bracket 16 which is provided with a head 17, 5 within the pillar, which head 17 abuts and may be rigidly secure to the backing plate 15 by any suitable means. The bracket 16 is provided with a pair of vertically spaced arms 18 extending toward the door end wall 14, externally of 10 the pillar, one end of a check arm 20 is pivoted to and between the arms 18 by a pivot pin 21, preferably a rivet.

Within the door 11, a retainer, casing or cage 22 is provided having outturned flanges 23 which 15 seat against a backing plate 24 which forms one wall of the retainer, the flanges 23, backing plate 24 and the hinge door end wall 14 being provided with aligning apertures to receive rivets 26 for rigidly securing the reenforcing plate and 20 cage to the door 11. The casing 22 includes a wall 22a, spaced from and substantially parallel to the door end wall 14 and the backing plate 24, door end wall 14 and the casing wall 22a 25 are provided with aligning openings or apertures through which extends the check arm 20 which projects into the door having therein a free end on which is provided and secured a buffer 27 preferably made of rubber or other suitable resilient material. 30

Positioned within the casing or retainer 22, a pair of yieldable cam-like bearing members or detents 28 are provided and are arranged to engage opposite sides of the check arm 20, these bearing members being yieldingly urged against 35 opposite sides of the check arm 20 by individual, resilient or yieldable means such as spring members 29. The spring members 29 are, in the present instance, bowed leaf springs, the crowns of which engage respectively the bearing members 28 and the ends of which springs 40 abut the opposite end walls 30 of the retainer or casing 22, see Fig. 5. Each of the cam-like bearing members 28 is provided with an extended or riser-like cam portion which may be 45 uniform throughout its length, as shown in Fig. 6, providing at the high surface thereof a socket engaging preferably rounded projection 31.

The arm 20 is provided with abutments 32 and 33 projecting from opposite sides of the arm 50 adjacent to but spaced from the resilient buffer or stop 27, the abutments being adapted to abut and cooperate with the bearings 28 to retard swinging open of the door 11. These abutments 32 and 33 also cooperate with the buffer or stop 55

head 27 to provide a recess to receive the bearing members 28 when the door is swung to wide or extreme open position. To provide an inexpensive arm 20, the abutments are preferably 5 made by pressing out of the arm 20 a pair of the abutments 32 spaced and between which the single abutment 33 is pressed out of the arm in the opposite direction to the abutments 32. These abutments 32 and 33 have rounded 10 surfaces and where they join the arm 20 provide oppositely directed sockets 35 and 36 in which the socket engaging projections 31 of the yieldable abutment or bearing members 28 are adaptable to engage.

15 In operation, when the door 11 is swung open far enough, the abutments 35 and 36 will come in contact with the yieldable members 28, the extended projections 31 of which will engage in the arm abutment sockets 35 and if the door 20 tends to open further, the abutments 32, 33 will 25 partially rotate the yieldable members 28 tending to move them away from each other and further tensioning the springs 29 which will act to retard the further swinging of the door. If 30 the door is swung open with sufficient force or if moved with the intention of opening it to its wide open position, the abutments 32 and 33 will partially rotate the yieldable members 28, forcing them apart until the abutments have 35 passed over the projections 31 after which these portions 31 will engage back of the abutments 32 in the sockets 36 as shown in Fig. 8 for yieldingly holding the door 11 in open position. When 40 the door 11 is again closed, the abutments pass back between the members 28 forcing them apart for necessary clearance and the members are partially rotated back to the positions shown in Fig. 7.

While I have shown and described my invention in detail it is to be understood that the same is to be limited only by the appended claims for many changes may be made without departing from the spirit and scope of the invention.

45 What I claim is:

1. In a door check device having a check arm provided with spaced abutments providing a recess therebetween, a check device cooperable with the check arm comprising, a retainer through 50 which the arm extends, a pair of bearings in said retainer for engaging opposite sides of the arm and having socket engaging projections, said bearing members being movable away from each other so that one of the abutments may pass 55 therebetween and the bearing members positioned in the recess formed by the spaced abutments, said socket engaging projections engaging said one abutment when said bearing members are positioned in said recess, and yieldable

means acting to hold said bearing members in engagement with opposite sides of said arm.

2. A door check and holding means comprising, an arm member having an abutment intermediate its ends providing a socket, a retainer member, one of said members being mounted on the door and the other of said members being mounted on the door frame, a pair of bearing members in said retainer and between which the arm extends, said pair of bearing members having extended socket engaging projections for engaging in the socket formed by said abutment, and a second abutment on said arm and cooperating with said first-named abutment to provide a recess therebetween to receive said bearing members, said bearing members being movable away from each other by said first-named abutment to position in said recess and biased toward each other.

3. A door check and holding means comprising an arm member having an abutment providing oppositely directed sockets, a retainer member through which the arm extends, said members being relatively movable and one of said members being carried by the door, a pair of rollers in said retainer and engaging opposite sides of said arm, said rollers having extended surface projections for engaging one or the other of said sockets, and spring means urging said rollers into engagement with opposite sides of said arm.

4. A door check and holding means comprising an arm member having an abutment providing oppositely directed sockets, a retainer member through which the arm extends, said members being relatively movable and one of said members being carried by the door, a pair of rollers in said retainer and engaging opposite sides of said arm, said rollers having extended surface projections for engaging one or the other of said sockets, and bowed leaf springs in said retainer 40 and urging said rollers toward each other into engagement with opposite sides of said arm.

5. A door check and holding means comprising an arm member having an abutment providing oppositely directed sockets and having a second abutment cooperable with the first to provide a recess, a retainer member through which the arm extends, said members being relatively movable and one of said members being carried by said door, a pair of bearing members 50 within said retainer and having cam surfaces engaging opposite sides of said arm, said bearing members being movable apart by said first abutment to engage in said recess to hold the door in an open position and having projections engageable in said sockets, and means yieldingly opposing movement apart of said bearing members.

FREDERICK J. WESTROPE.
